UNITED STATES PATENT OFFICE.

JOHN G. PERRIN, OF DETROIT, MICHIGAN.

DESIGN FOR A WIND-SHIELD.

43,475.

Specification for Design.

Patented Jan. 21, 1913.

Application filed November 11, 1912. Serial No. 730,819. Term of patent 7 years.

To all whom it may concern:

Be it known that I, JOHN G. PERRIN, a citizen of the United States, and a resident of Detroit, county of Wayne, State of Michigan, have invented a new, original, and ornamental Design for Wind-Shields, of which the following is a specification, reference being had to the accompanying drawing, forming a part thereof.

In the drawings: Figure 1 represents a

front elevation of a wind shield embodying my new design; and Fig. 2 represents an end view thereof.

I claim:

The ornamental design for a wind shield, as shown.

JOHN G. PERRIN.

Witnesses:

S. A. THORNTON,
MABEL J. COOPER.
